MULTIPLAYING GRAPHOPHONE

Application filed June 14, 1921. Serial No. 477,404.

This invention relates to multi-playing graphophones wherein provision is made for automatically playing in succession a plurality of records without requiring manual operation after the device is started, and pertains more particularly to improvements in my pending application upon multi-playing graphophone, Serial Number 442,034, filed February 3, 1921.

10 The objects of the invention are to provide a machine of this type adapted to play a plurality of records in succession, means being provided for successively feeding one record at a time to the turn table after the 15 playing of the preceding record is finished, means being also provided for automatically raising the sound reproducer and tone arm from engagement with the record after the playing of each record, and moving the same 20 beyond the periphery of the turn table to allow the next record to be dropped into position upon the turn table, the tone arm being then automatically moved into position and lowered upon the record to start playing.

25 The machine is so constructed that a plurality of records may be placed in position thereon and successively played without further attention from the operator, or any desired number of the records may be played 30 after which the machine is automatically stopped or one record may be repeated indefinitely, as desired, or the machine may be manually stopped at any time, or if desired, one record may be played in the usual manner as on the ordinary phonograph.

The present application relates more particularly to certain improvements in the record holding and feeding mechanism, non-vibrating mechanism between the reproducer 40 and the swinging and lifting mechanism to prevent vibrations from the operating mechanism from being reproduced through the horn or amplifier, friction mechanism to prevent accidental movement of the tone arm 45 until the needle engages the record and an automatic stop to prevent the needle from dragging across the record, means for manually tripping the stopping mechanism and for stopping the mechanism after the play- 50 ing of any record, together with other details

of construction of the various parts of the device.

With these objects in view the invention consists in the construction and arrangement of parts, hereinafter described, and illustrated in the accompanying drawings, it being understood that various changes in the form and details of construction may be made within the scope of the appended claims.

The invention thus set forth in general 60 terms is illustrated in the accompanying drawings, in which—

Figure 1 is a fragmentary plan view of a graphophone constructed in accordance with 65 the invention;

Fig. 2, a side elevation of a portion of the device, parts being broken away for purpose of illustration;

Fig. 3, a section on the line 3—3, Fig. 4;

Fig. 4, a section on the line 4—4, Fig. 3;

Fig. 5, a section on the line 5—5, Fig. 4;

Fig. 6, a detail of a portion of the record dropping mechanism and the associated parts, on line 6—6, Fig. 3;

Fig. 7, a detail view as indicated by line 75 7—7, Fig. 3, showing a portion of the regulating mechanism;

Fig. 8, a section on the line 8—8, Fig. 3;

Fig. 9, a perspective view of a portion of the mechanism which controls the releasing 80 of the clutch;

Fig. 10, a vertical sectional view of the record holding and feeding shaft;

Fig. 11, a transverse sectional view through the same on an enlarged scale; and

Fig. 12, a section on the line 12—12, Fig. 3.

Fig. 13, a fragmentary perspective view of the friction latch mechanism to prevent accidental movement of the tone arm until the reproducer needle engages the outer periphery or starting groove of the record.

Similar numerals of reference indicate corresponding parts throughout the drawings.

The usual cabinet within which the motive 95 mechanism of the graphophone is contained is indicated generally by the numeral 1, the upper and lower walls 2 and 3, respectively, being spaced apart in any suitable manner for housing the mechanism.

The tone arm 4 is swiveled upon the vertical tube 5, which is slidably connected with the tube 5^a which connects with the amplifier. The reproducer 6 which may be of any desired construction, is carried upon the tone arm in the usual manner, a fibre collar 6^a being provided at the connection of the tone arm and reproducer to prevent vibrations of the mechanism from being reproduced through the amplifier or horn. A depending post 7 is carried by the free end of the tone arm and a link 8 is pivoted thereto and provided at its free end with the socket 9, within which is mounted a ball 10 carried at the 10 extremity of the lever 11 which is pivoted intermediate its extremities upon the vertical rock shaft 12.

The lever 11 is provided with a pivoted portion 13 hinged as at 14 in such a manner 20 as to allow the hinged joint to operate as the free end of the lever is moved upward, but preventing such free end of the lever and the reproducer 6, and tone arm 4, carried thereby from moving down below the plane of the 25 turntable without raising the hinged section 13, such hinged section and its connections also permitting the operator of the machine to manually raise the tone arm independently of the pivoted section 16 and its actuating 30 mechanism for the purpose of inserting a new reproducer needle.

A depending rod 15 is pivoted at 16 to the free end of the hinged section 13 of the lever, and the lower portion of said rod comprises 35 two hinged sections 17 and 18, the pivots 19 and 20 thereof being located in planes at right angles to each other, thus allowing pivotal movement in two directions of the upper portion of the rod, made necessary by 40 the degree of inclination of the slot 214 in the upper end of the rock shaft 12.

The lower section 18 is vertically, slidably mounted through the bearing portions 21 of the radial arms 22 and 23, said radial arms 45 being fixed upon the rock shaft 12 within the cabinet, said rock shaft extending to the bottom wall 3 and being journaled in the bearings 24 and 25.

A disk 26 is journaled upon the rock shaft 50 12 above the lower bearing and a similar disk 27 is spaced above the disk 26 and journaled upon the rock shaft, each of said disks being provided with a bevel gear portion 28 meshing with the bevel pinion 29 which is fixed 55 upon the horizontal clutch shaft 30.

The shaft 30 is journaled in the bearings 31 and 32 which are mounted upon the plate 33 connected to the lower wall of the cabinet. A bevel gear 34 is rotatably mounted upon 60 the shaft 30 and has integrally formed thereon the clutch member 35.

The co-acting clutch member 36 is splined upon the shaft 30 and arranged to be moved into engagement with the clutch member 35 65 by means of the lever 37, which is pivoted in-

termediate its extremities upon the post 38, the free end thereof being connected by means of a link 39 to the lever 40 which latter is pivoted intermediate its extremities upon the post 41.

The gear 34 meshes with a bevel pinion 42 fixed upon a vertical shaft 43, a pinion 44 being also fixed upon said shaft and meshing with a pinion 45 driven in any suitable manner from the motor which is usually provided for operating the graphophone. 70

An arm 46 is fixed upon the rock shaft 12 above the upper disc 27 and is provided with a depending portion 47 (see Fig. 9) having a set screw 48 arranged to engage the finger 49 of the latch 50 pivoted as at 51 upon the lever 40. The finger 52 of the latch is provided on its under side with a notch 53 arranged to normally receive and hold the lip 54 of the supplemental arm or lever 55 which latter is pivoted at 56 upon the under side of said lever 40. A leaf spring 57 is connected as at 58 to the opposite side of the lever 40 and bears against the upwardly extending finger or arm 49 of the latch 50, thereby resiliently and normally holding the latch in a position shown in Figs. 5 and 9 of the drawings, a leaf spring 59 being connected as at 60 to the side of the lever 40 and engaging the supplemental lever or arm 55 to normally hold the latter in alignment with the lever 40 and in position to be engaged by the finger 52 of the latch 50. 80

A stop arm 61 is mounted upon the post 41 beneath the pivoted lever 40 by means of a set screw 62, said stop arm 61 being provided at one end with an upturned lip 63 carrying an adjustable stop screw 64 for adjusting the throw or stop position of the outer end of the lever 40 at the desired point. 90

A finger 65 is pivotally connected at its inner end to a collar 66 fixed upon the rock shaft 12 between the disks 26 and 27, said finger extending beyond the peripheries of said disks, and being located in the path of the pin 67 which is fixed upon the upper surface of the lower disk 26, the spring 66^a (see Figs. 3 and 4) upon the top of the lower disk being arranged to engage the fixed collar 66 to move the tone arm needle into the record 115 initial playing groove. 110

An adjustable inclined block 68 is slidably mounted upon the guide 69, fixed upon the bottom wall of the cabinet in the path of the free extremity of the arm 65. For 120 the purpose of adjusting the block 68, the rod 70 is located vertically through the cabinet and provided with an arm 71 having a slot 72 which receives the pin 73 upon the block 68, a button 74 being provided upon the upper end of the rod and having an indicating finger 75 which cooperates with the dial 76 indicating the size of the record for which the machine is set. 125

The usual turn table 77, upon which the 130

records are placed for playing, is fixed upon the rotatable tubular shaft 78 which extends through the upper wall of the cabinet and is journaled in suitable bearings 79 and 80, the 5 pinion 45 being fixed upon said shaft and operatively connected to the driving mechanism.

Collars 81 and 82 are fixed upon the tubular shaft in position to engage the bearings 79 10 and 80 respectively, in order to prevent vertical movement of the shaft.

A vertically movable rod 83 is slidably mounted within the tubular shaft 78 and is provided near its upper portion with the reduced shank 84, the upper extremity of the 15 rod being again enlarged as shown at 85.

The tubular shaft 78 is provided with a plurality of superposed, spaced rows of inwardly inclined apertures 86, balls 87 being 20 mounted in said apertures and arranged to normally engage the enlarged upper end 85 of the rod. As the rod 83 is moved upwardly, one row of said balls at a time will be allowed to drop inwardly, engaging the 25 reduced shank 84 of the rod.

The disk records 88 are each provided with the usual central aperture 89 which is of sufficient diameter to receive the tubular shaft 78, and to engage the balls 87 when they are 30 held in the outer position by the enlarged portion 85 of the rod.

A leaf spring 90 is mounted in a vertical socket in the tubular shaft 78 and provided at 35 its upper portion with a pin 91 arranged to selectively engage the notches 92 formed in the rod 83 and corresponding in number with the records to be placed upon the shaft. The lower extremity of the rod is preferably tapered or coned as at 95.

40 A ratchet 96 (see Figs. 3 and 6) is mounted upon a stem 97 journaled in a bearing 98 upon the lower wall of the cabinet, said ratchet being beneath and eccentric to the rod 83, a cam 99 being provided upon said ratchet, 45 the conical end of the rod 83 traveling upon the upper surface of said cam. A spring locking pawl 100 is provided for preventing the ratchet from accidentally turning.

An arm 101 is pivoted upon the stem 97 and 50 provided with a pawl 102 normally held in engagement with the ratchet teeth by means of a spring 103, a link 104 connecting said arm with a bell crank 105 pivoted upon a post 106 and mounted upon the bottom of the 55 cabinet, the other arm of said bell crank being connected by a link 107 with an arm 108 pivoted upon the stem 109, carried upon the bottom of the cabinet, a ratchet 110 being rotatably mounted upon said stem, a pawl 111 60 carried upon the arm 108 being normally held in engagement with said ratchet by means of the spring 112.

A disk 113 is fixed upon and concentric with the ratchet 110 and provided with a 65 plurality of pins 114 corresponding in num-

ber to the number of records which the machine is adapted to play, said pins increasing uniformly in length from the first to the sixth pin, as shown in Fig. 3.

A spring locking pawl 115 is provided for 70 preventing accidental backward movement of the ratchet. A flat bar 116 is pivoted at one extremity as at 117 to the bottom of the cabinet and is provided with the keepers 118 and 119 through which the rod 120 is slidably 75 mounted.

A trigger 121 is pivoted upon the bar 116, the inner extremity thereof being arranged to be normally seated in the notch 122 formed in the rod 120, the spring 123 normally holding the trigger in this position. The function of the trigger 121 is to automatically stop the machine when the desired number of records have been played, and when thrown out by one of the arms 114 in accordance with the position in which the parts are set through the rod 126 and indicator 128, as now described. The free extremity of the bar 116 is connected by the link 124 with the arm 125 fixed upon the vertical rod 126, said 80 rod extending through the upper wall of the cabinet and being provided with a finger button 127 having the indicator 128 which cooperates with the dial 129 upon which are the figures indicating the number of records 85 which may be played upon the machine before it is automatically stopped.

The starting lever 130 is mounted above the top wall of the cabinet upon the vertical rod 131 which extends through the cabinet to the bottom wall thereof, being journaled in a bearing 132 mounted upon the bottom wall, an arm 133 being fixed upon the lower end portion of said rod and arranged to engage the rod 120 to move the same longitudinally 105 through the keepers 118 and 119.

The free end portion of the bar 116 is mounted beneath the guide 134, the rod 120 extending over said guide. A plurality of 110 sockets 135, corresponding in number to the records to be played upon the machine, are provided in the upper face of the bar 116 and arranged to be selectively engaged by the spring pressed plunger 136 carried in the guide 134, for the purpose of preventing accidental movement of the bar after it has been set at the desired point.

A rod 137 extends through the cabinet having a bearing 138 upon the lower wall thereof, the upper extremity of said rod being provided with a lever 139 by means of which the rod may be rotated, an arm 140 being fixed upon the lower end portion of the rod and arranged to engage the pin 141 upon the trigger 121 in order that the graphophone may be stopped manually at any time.

The speed regulating mechanism, best illustrated in Fig. 7, comprises the bracket 142 suspended from the under side of the top wall of the cabinet and having pivotally 130

mounted therein the bell crank 143 which is adjusted through the adjusting screws 144 extending through a threaded bearing 145 and provided with an operating button 146 having an indicating finger 147 which cooperates with the indicating dial 148 upon the top of the cabinet.

An arm 149 is pivoted at 150 upon the bracket and is connected to the bracket by 10 means of the coil spring 151, a plunger 152 being slidably located through a suitable bearing in said arm and engaging the depending arm 153 of the bell crank. A lever 154 is pivoted at 155 to the lower end of the arm 149, the upper end of said lever engaging the plunger 152 and the lower end thereof engaging the extremity of the rod 120.

A rock shaft 150 is fixed to the arm 149 and has fixed thereon a rock arm 150^a which 20 engages the starting arm 150^b of the brake actuating shaft of the motor and is arranged to be rocked to release and start the motor in the usual manner.

25 A ratchet 156 is mounted upon a stem 157 journaled in a suitable bearing upon the lower wall of the cabinet, an arm 158 being pivotally mounted upon said stem and connected by means of a link 159 with the bell 30 crank 105. A spring pressed pawl 160 is mounted upon the arm 158 and engages the ratchet 156, a locking pawl 161 also engaging said ratchet for preventing accidental movement thereof.

35 A cam 162 is formed integrally with the ratchet 156 and is engaged by the depending rod 163 which is connected to the ring 164 mounted upon the tube 5 which carries the tone arm, said tube being slidably mounted 40 over the tube 5^a which is connected with the amplifier in the usual manner; suitable bearings are mounted upon the tube 5^a for slidably supporting the rod 163. In this way the pivoted portion of the tone arm 4 is successively 45 elevated with the dropping and building up of the records on the turn table and the tone arm 4 is maintained in a substantially constant relative position to the record being played.

50 A lever 165 is pivoted at one extremity upon the bottom of the cabinet as shown at 166, a trigger 167 being pivoted intermediate its extremities upon the central portion of said lever as shown at 168, said trigger being 55 arranged to be engaged by the pin 169 upon the disk 27. The opposite extremity of the trigger is connected as at 169^a to the link 170 which connects to the extremity of the arm 101. Stop pins 171 and 172 are provided upon the bottom wall of the cabinet 60 to be engaged by the lever 165, the coil spring 173 which is connected to the trigger normally holding the trigger 167 against the stop 167^a.

65 A rod 174 extends vertically through the

cabinet and is provided at its lower portion with a fixed arm 175 which is connected by means of a link 176 with the lever 165, a button 177, being provided upon the upper end of the rod and having an indicator finger 70 75 which cooperates with the dial 179.

By turning the rod to move the trigger into, or out of the path of the pin 169 upon the disk, the device may be set to play the six records successively, or to repeat one record indefinitely.

80 A spring pressed trigger 180 is mounted in a base 181 fixed upon the bottom wall of the cabinet, said trigger being arranged to engage the finger 182 upon the arm 23, a stud 184 being carried by said trigger and extending through a slot 185 in the base 181, and arranged to be engaged by the lower end of the rod 15. In order to assure the trigger engaging the finger 182, the upper end thereof is corrugated as shown at 186.

85 The disk 27 is provided in its periphery with a cam surface 187 at one extremity of which is provided a notch 188, the peripheral portion of the disk adjacent to said notch as 90 at 189 being of less thickness than upon the other side of the cam surface 187 as at 190. A roller 191 is mounted upon the lower section of the rod 15 and arranged to engage the cam surface of the disk 27, the tone arm 95 and reproducer being raised and lowered through the lever 11 by means of this roller and cam.

95 A curved plate 192 is suspended upon brackets 193 at a point adjacent to the rod 15. A bracket 194 is mounted at 195 upon the arm 22 and provided with an upwardly extending portion 196 at its extremity within which is pivoted the catch or trip lever 197. An arm 198 is fixed to the bracket 194 and provided with a pad of fibrous material 199 arranged to engage the upper surface of the plate 192 to hold the tone arm against accidental movement until the reproducer needle 100 engages the record.

100 A pin 200 is provided in the lower section of the rod 15 and arranged to operate the catch lever 197, a pin 201 being provided in the extremity of the arm 22 for engagement with said catch. A collar 202 is fixed upon the rod 15 and a coil spring 203 is interposed between said collar and the upper surface of the arm 22 for the purpose of normally holding the rod in the raised position with the roller 191 in engagement with the cam surface of the disk 27.

110 A finger 204 is provided upon the tone arm and arranged to engage the stop pin 205 mounted upon the cabinet for the purpose of limiting the outward movement of the tone arm when the same is swung into the inoperative position to allow a new record to be dropped upon the turn table.

115 The operation of the device is as follows: With the tone arm and the connecting mech- 130

anism in the position shown in dotted lines in Fig. 1, one record is placed upon the turn table of the phonograph, the rod 83 being then moved to its raised position, allowing all of the balls 87 to drop inwardly into engagement with the reduced portion 84 of the rod. Five records are then placed upon the tube 78 and the rod lowered into the position shown in Fig. 10, the enlarged portion 85 thereof forcing the balls outwardly, each set of balls sustaining one record.

The rod 126 is then rotated, moving the finger 128 thereon into position adjacent to the number upon the dial 129, designating the number of records desired to be played. With this operation, the bar 116 will be swung upon its pivot 117 through the arm 125 and link 124, moving the trigger 121 the desired distance from the disk 113 and the trigger actuating arms 114.

The starting rod 131 is then rocked, by means of the lever 130 thereon, in the direction of the arrow shown in Fig. 1, the arm 133 (see Fig. 3) upon said rod engaging the rod 120 and sliding the same longitudinally through the keepers 118 and 119, engaging the notch 122 thereon with the trigger 121.

At the same time, the other extremity of the rod 120 will engage the depending arm 30 of the lever 154 and throw the mechanism shown in Fig. 7, rocking the shaft 150 and the arm 150^b thereon, said arm engaging the brake actuating or starting arm 150^b of the motor, starting the motor in the usual manner.

The tone arm is then carried into position and lowered by the mechanism hereinbefore referred to and the first record is played, then as the playing of this record is completed, 40 the tone arm and reproducer will have reached the position shown in full lines in Fig. 1. With this operation, the shaft 12 is moved into position causing the screw 48 upon the arm 46 to engage the catch 49, releasing the finger 54 of the arm 55 from engagement with said catch, the spring 208 moving the member 36 into engagement with the cooperating member 35, the lever 37 through the link 39 throwing the lever 40 over the pin 50 upon the upper disk 27. The shaft 30 is then rotated, and through the bevel pinion 29, the disks 26 and 27 are rotated in the directions of the arrows shown in Figs. 3 and 5, the arm 55 upon the lever 40 being engaged by the pin 209 upon the top disk 27, and swung upon its pivot out of the path of said pin and as the pin passes out of engagement with said arm, the spring 59 will throw the arm back into the normal position and into engagement with the catch 49.

The corrugated upper surface of the trigger engages with the finger 182, preventing the needle from being dragged across the record by the cam pushing against the roller 191, holding the lever 11 which operates the

tone arm, against horizontal movement until the reproducer has been raised, moving the needle out of engagement with the record.

As this action takes place, the depression of the rod 15, which is at this time directly over the pin 184, will depress the trigger 186 below the finger 182, releasing the arm 23 and allowing the lever to be swung into the outward position, swinging the tone arm into the position shown in dotted lines in Fig. 1.

If it is desired to repeat the first record indefinitely, the rod 174 is left in the position shown in Figs. 1 and 3, holding the trigger 167 out of the path of the pin 169 upon the lower disk 26. If, however, it is desired to play the several records in succession, the rod is turned, moving the finger 178 into the dotted position shown in Fig. 1, throwing the trigger 167 into the path of the pin 169.

With the parts in this adjusted position, the pin 169 will engage the trigger 167, as the disk 26 is rotated and through the link 170 and pawl 102 will move the ratchet 96 one notch, raising the rod 83 by means of the cam 99, allowing the lowermost set of balls 87 to drop inwardly against the reduced portion 84 of the rod, permitting the lowermost record to drop upon the turn table.

When the disk 113 is moved to such position that one of the pins 114 will engage the extremity of the trigger 121, said trigger will be thrown out of engagement with the notch 122 in the rod 120, the spring 151 throwing said rod out of engagement with the trigger and rocking the shaft 150, moving the rock arm thereon out of engagement with the motor starting lever, stopping the motor.

At the same time the ratchet 156 will have been operated in the same manner through the link 159 and pawl 160 and through the cam 162 and rod 163, the tone arm will be raised sufficiently to permit the needle of the reproducer to engage the next record at the normal angle.

During this same operation the ratchet 110 will be rotated through the pawl 111 and link 107 moving the disk 113 one-sixth of a complete revolution. Prior to the dropping of the record upon the turn table, the tone arm will have been swung into the position shown in dotted lines, Fig. 1, by the roller 191 upon the rod 15 being received and carried within the notch 188 in the disk 27. As the raised cam portion 189 upon the disk 27 engages the roller upon the rod 15, the lever 11 pivoted upon the upper end of said rod will be tilted, raising the reproducer clear of the record.

The pin 67 upon the upper side of the lower disc 26 will, upon the rotation of the latter, come into engagement with the pivoted arm 65, thereby rotating the shaft 12 from right to left or anti-clockwise and correspondingly swinging the tone arm to the starting position. As the reproducer is car-

ried over the outer edge of the record in a position to start playing (see dotted lines in Fig. 1) the vertically movable arm or finger 65 will be carried up the inclined portion of the stop 68, thereby causing the arm 65 to be raised to clear the pin 67 (permitting the pin 67 to pass under the same in disengagement) and consequently stopping the tone arm and reproducer at this outer or starting point. The tone arm will then be lowered by means of the recess surface 187 of the upper disc 27 receiving the roller 191 carried upon the rod 15 and consequently lowering the lever section 11 and connected reproducer and tone arm for the starting of the playing of the next record. As the tone arm swings into the starting position friction takes place between the pad 199 and the plate 192 (see Fig. 13) by the lowering of the rod 15 by reason of the raised portion 190 of the disc 27 (see Fig. 4) engaging the roller 191 carried upon the lower sections 17 and 18 of the lever actuating rod 15. This action throws the trip or nose member 196 against the depending pin 201 in the arm 22 holding the latter by friction until the needle in the reproducer engages the record; then as the rod 15 is raised in lowering the reproducer carried on the opposite end of the lever 11 the pin 200 strikes the trip lever 197, raising the latter and thereby causing the upwardly extending nose of the lever 197 to become disengaged from the pendant pin 201 and releasing the frictional engagement between the pad 199 and the plate 192. (See Fig. 5). The spring 66^a then comes into contact with the lower portion of the lug of the collar 66, rotating the shaft 12 in an anti-clockwise direction carrying the lever 11 horizontally and thereby finally throwing the tone arm 4 over inwardly and horizontally to the outer periphery of the record toward the first or starting grooves thereof and sufficiently to bring the needle therein at which instant the spring 66^a passes free for the normal playing of the record.

It will also be observed that when the tone arm 4 has been moved through its connections to the full line position shown in Fig. 1 of the drawings, concluding the playing of a record, and the clutch members 35 and 36 have been held in their open position during the playing of the record by the action of the pin 209 of the upper disc 27 in engagement with the latch plate 55 (see Figs. 5 and 9) carried on the arm 40 and transmitted by the latter through the links 39 to the arm 37 (the discs 26 and 27 being locked as against the independent relative movement by the connecting gear 29) the rock shaft 12 will have been carried with the arm 46 to substantially the position shown in Figs. 4 and 5 of the drawings. Accordingly as the screw 48 of the arm 46 strikes

the arm 49 of the pivoted latch the latch member 52 will be elevated releasing the catch 54 of the longitudinally pivoted latch plate 55, thereby permitting such auxiliary or supplemental lever or latch plate to swing horizontally through the connection of the pin 209, allowing the latter to pass under the arm of the lever 40 and the latter then being free, it will together with its connections 39 and 37 react or take a reversed position through the pressure exerted by the spring 208 thus throwing the clutches 35 and 36 into engagement. After the supplemental lever or latch plate 55 has been moved clear at its free end of the pin 209 such latch plate 55 will be swung horizontally by the leaf spring 59 to its original position and be automatically engaged by the latch 52 of the pivoted catch. The clutch members 35 and 36 being in engagement it will be understood that the lower and upper discs 26 and 27, respectively, are being rotated in opposite directions, the upper disc 27 rotating in a clockwise direction and the lower disc 26 in an anti-clockwise direction.

When the discs 26 and 27 start in this movement and the tone arm is in full line position shown in Fig. 1 of the drawings, the cam surface 190 of the upper disc 27 will come into engagement with the roller 191 and thereby depress the rod 15 which is at this time directly over the pin 184 and depressing the trigger 186 below the finger 182 will release the arm 23 thereby permitting the lever 11 to be swung to the outward position by the mechanism hereinbefore referred to, carrying with it the tone arm to the position shown in dotted lines in Fig. 1. Just after this action takes place, the pin 169 of the lower disc 26 has engaged the lever 167 thereby simultaneously through the connected arms and links 170, 104 and 159 moving the ratchets 96 and 156 one notch and raising the rod 83 for the release of the next record which falls upon the record just played, and elevating the movable section 5 of the tone arm 4 sufficiently to permit the tone arm to be moved inwardly and lowered to its initial position on the outer periphery of the record just dropped and as now described. During the movement just described the lower disc 26 through the pin or projection 67 has engaged the arm 65 moving it to the stop 68 thereby carrying the tone arm inwardly toward the outer periphery of the new record and during such rotation the disc 27 through its recess 187 will have received the roller 191 carried on the lower section of the pin 15, thereby lowering the sound box 6 with its stylus and the tone arm 4 to the outer periphery of the record. Supplementing such action the lower disc 26 through its spring 66^a engages the lug portion of the collar 66 carrying the vertically movable arm 55 upon the

inclined stop 66 (see Fig. 4) for the final location and horizontal movement of the stylus into the initial playing groove of the record.

5 As shown in Fig. 10 of the drawing, it will be noted that the tubular shaft 78 is provided at its upper extremity with a tapered or conical head 210 which assists in placing the records upon the shaft by quickly centering the records as they are placed upon the shaft. It will also be seen that the upper extremity of the enlarged portion 85 of the rod 83 is provided with a pin 211 which extends through the vertical slots 212 in the upper end portion of the tubular shaft, said pin being provided at its extremities with the heads 213 which may be grasped by the operator for moving the rod downwardly when it is desired to place a plurality 10 of records upon the shaft.

Attention is called to the fact that the lever 11 is pivoted to the upper end of the shaft 12 in an inclined slot 214, the pivot thus being at a slight angle to the horizontal, 15 this being for the purpose of lowering the reproducer vertically to bring the needle always to the same relative position upon the record, regardless of the number of records built up upon the turn table and to 20 compensate therefor.

By means of the manually operated stopping lever 139 the machine may be operated in the same manner as any single playing machine by placing the lever 177 in the 25 "repeat" position shown in Fig. 1.

It will be noted that the stem 98, upon which the ratchet and cam, which operate to lower the records, are mounted, may be adjusted vertically by means of the threaded 30 extremity 220 of said stem, which engages the internally threaded bearing 221 mounted in the lower wall of the cabinet, a jam nut 222 being provided upon said threaded extremity of the stem for holding the same in 35 any adjusted position.

I claim:

1. A graphophone including a cabinet, a motor driven turn-table, a tubular shaft extending through said turn-table, means on 40 said tubular shaft for supporting a plurality of records in spaced relation above said turn-table, a tone arm and reproducer mounted adjacent to said turn-table, means within said tubular shaft for automatically lowering a 45 record upon the turn-table as the tone arm is swung outwardly, and means for manually actuating said record supporting and lowering means in said tubular shaft independently of said automatic actuating means.

50 2. A graphophone including a cabinet, a motor driven turn table, a tubular shaft extending through said turn table, superposed sets of balls provided in said tubular shaft for supporting a plurality of records above 55 said turn table, a rod within said tubular

shaft arranged to engage said balls to lower a record upon the turn table, and means for holding the rod out of engagement with the balls after the last record has been dropped to allow all of the records to be removed therefrom.

3. A graphophone including a cabinet, a motor driven turn table, a tubular shaft extending through said turn table, superposed sets of balls upon said shaft arranged to support a plurality of records above the turn table, a rod within said tubular shaft arranged to engage said balls, means for moving the rod vertically within the tubular shaft for successively releasing each set of balls to lower a record upon the turn table after the tone arm is swung outwardly, and means for moving said rod downwardly through the tubular shaft to replace records thereon.

4. A graphophone including a cabinet, a motor driven turn table, a tubular shaft extending through said turn table, means including radially movable balls within said shaft for holding a plurality of records spaced above the turn table, means within said tubular shaft for successively releasing said balls and for lowering one record at a time to the turn table and a tapered upper extremity upon said tubular shaft to assist the placing of records upon said shaft.

5. A graphophone including a cabinet, a motor driven turn table, means for building up records in superposed relation on the latter, a tone arm and reproducer mounted adjacent to said turn table, a lever connected to said tone arm, a shaft upon which said lever is pivoted intermediate its ends, the pivotal connection being located at an angle to the horizontal to compensate for the building up of said records with respect to the initial position of the reproducer and tone arm, means for automatically rocking said lever and rotating said shaft to raise the tone arm and reproducer and swing the same outwardly beyond the periphery of the turn table as the playing of each record is completed, and means for rotating said shaft and rocking said lever to swing the tone arm and reproducer back to the playing position and lower them into engagement with the record.

6. A graphophone including a cabinet, a motor driven turn-table including a record, a tone arm and reproducer mounted adjacent to said turn table, means for automatically raising said tone arm and reproducer and swinging the same outwardly beyond the periphery of the turn table as the playing of each record is completed, means for automatically moving the tone arm and reproducer back to the playing position and lowering them into engagement with the record after each record has been lowered upon the turn table, and a friction mechanism to prevent accidental movement of the tone arm

- until the reproducer needle engages the record.
7. A graphophone including a cabinet, a motor driven turn table including a record, a tone arm and reproducer mounted adjacent to said turn table, means for automatically raising said tone arm and reproducer and swinging the same outwardly beyond the periphery of the turn table as the playing of each record is completed, means for automatically moving the tone arm and reproducer back to the playing position and lowering them into engagement with the record, and an automatic stop provided with a corrugated surface to prevent the needle from dragging across the record.
8. A graphophone including a cabinet, a motor driven turn table including a record, a tone arm and reproducer mounted adjacent to said turn table, a lever connected to said tone arm, a shaft upon which said lever is mounted intermediate of its ends, a pair of disks loosely mounted upon said shaft and arranged to be rotated in opposite directions, means for automatically rotating said disks as the playing of each record is completed, means operated by said disks for automatically swinging the tone arm and reproducer outwardly beyond the periphery of the turn table as the playing of each record is completed, means operated by said disks for automatically moving the tone arm and reproducer back to the playing position and lowering them into engagement with the record, table as the playing of each record is completed, means operated by said disks for automatically stopping the rotation of said disks after the tone arm has been lowered to the playing position, a collar upon said shaft and a spring upon one of said disks for engagement with said collar to move the tone arm to throw the needle of the reproducer into the playing groove of the record.
9. A graphophone including a cabinet, a motor driven turn table including a record, a tone arm and reproducer mounted adjacent to said turn table, a lever connected to said tone arm, a shaft upon which said lever is mounted intermediate of its ends, a pair of disks loosely mounted upon said shaft and arranged to be rotated in opposite directions, means for automatically rotating said disks as the playing of each record is completed, means operated by said disks for automatically swinging the tone arm and reproducer outwardly beyond the periphery of the turn table as the playing of each record is completed, means operated by said disks for automatically moving the tone arm and reproducer back to the playing position and lowering them into engagement with the record, means for automatically stopping the rotation of said disks after the tone arm has been lowered to the playing position, a rod connected to the free end of said lever, a roller upon said rod arranged to engage the under surface of one of said disks, a friction mechanism to prevent accidental movement of the tone arm until the reproducer needle engages the record and a disk having a cam surface arranged to engage the roller upon said rod to operate said friction mechanism.
10. A graphophone including a cabinet, a motor driven turn table including a record, a tone arm and reproducer mounted adjacent to said turn table, a lever connected to said tone arm, a shaft upon which said lever is mounted intermediate of its ends, a pair of disks loosely mounted upon said shaft and arranged to be rotated in opposite directions, means for automatically rotating said disks as the playing of each record is completed, means operated by said disks for automatically swinging the tone arm and reproducer outwardly beyond the periphery of the turn table as the playing of each record is completed, means operated by said disks for automatically moving the tone arm and reproducer back to the playing position and lowering them into engagement with the record after each record has been lowered upon the turn table, means for automatically stopping the rotation of said disks after the tone arm has been lowered to the playing position, a rod connected to the free end of said lever, a roller upon said rod arranged to engage the under surface of one of said disks, a friction mechanism to prevent accidental movement of the tone arm until the reproducer needle engages the record and a disk provided with a cam surface having a notch arranged to engage said roller to swing the tone arm from the end of the playing position clear of the record beyond the periphery of the turn table.
11. A graphophone including a cabinet, a motor driven turn table including a record, a tone arm and reproducer mounted adjacent to said turn table, a lever connected to said tone arm, a shaft upon which said lever is pivoted intermediate its ends, a pair of disks loosely mounted upon said shaft, means for automatically rotating said disks as the playing of each record is completed, a cam upon one of said disks, a rod connected to the other end of said lever and provided with a roller engaging said cam, said rod being composed of three pivoted sections, the pivots in said sections being located in planes at right angles to each other, said cam and rod being arranged to automatically rock said lever, means for rotating the shaft to raise the tone arm and reproducer and swing the same outward beyond the periphery of the turn-table, after each record is completed, and means for rotating the shaft and rocking the lever to move the tone-arm and reproducer back to the playing position after each record has been lowered upon the turn table.
12. In a graphophone, a turn-table, a tubular shaft extending upwardly from the center of the turn-table and provided with spaced rows of inwardly inclined openings,

balls mounted in said openings, a rod in said shaft adapted when in one position to hold said balls in a record engaging projected position and in another position to hold said balls in a record releasing position, and means for shifting said rod.

13. In a graphophone, including a turn-table, a centrally located tubular shaft extending upwardly from the turn-table and provided with spaced sets of radially movable balls each set being adapted in one position to engage and support a record from the central opening thereof when mounted on said tubular shaft and in another position to release the record and allow it to drop upon the turn-table, and vertically reciprocating means within said tubular shaft for controlling the radial positions of said balls.

14. In a graphophone including a turn-table, and a tone arm and reproducer, and means for automatically moving the tone arm and reproducer into and out of engagement with the records, a tubular shaft extending through the turn-table, means upon and operable from within said shaft for supporting a plurality of records in spaced relation thereon above the turn-table and means within said tubular shaft for automatically lowering a record upon the turn-table after the tone arm and reproducer are swung out of engagement with the preceding record.

15. In a graphophone including a turn-table and a record, and a tone arm and reproducer, a tubular shaft extending through the turn-table, a superposed set of balls provided in said shaft for supporting a plurality of records above said turn-table, a rod within said tubular shaft arranged to engage said balls to hold them in engagement with the records, said rod having a reduced portion arranged to allow the balls to drop inwardly out of engagement with the records, means for moving the rod vertically in the tubular shaft to disengage the records and allow the same to drop upon the turn-table and means for holding the reduced portion of the rod in engagement with the balls after the last record has been dropped to allow all of the records to be removed from the tubular shaft.

16. In a graphophone of the character described in claim 15, projections on the rod projecting from and slideable in the tubular shaft for manually moving the rod downwardly through the tubular shaft to engage the balls with a new set of records.

17. In a graphophone of the character described in claim 14, a cam operatively engaging the means within the tubular shaft for lowering the records and means for automatically operating said cam after each record is played.

18. In a graphophone of the character described in claim 15, a cam operatively engaging the rod and means for automatically operating said cam after each record is played.

19. In a graphophone of the character described in claim 15, a cam operatively engaging the rod and means for automatically operating said cam after each record is played, and means for adjusting said cam vertically.

20. In a graphophone comprising a turn-table including a record, a tone arm and a reproducer, a rock shaft operatively connected to the tone arm, means for automatically engaging said rock shaft after each record is played, to swing the tone arm beyond the periphery of the turn-table, a radial arm mounted upon the rock shaft, means for engaging said arm to move the tone arm back to the playing position and an inclined block arranged to be engaged by said arm to free the same from engagement with the operating means to stop the movement of said rock shaft as the tone arm and reproducer reach the playing position.

21. In a graphophone of the character described in claim 20, means for adjusting the inclined block in order to bring the tone arm and reproducer into the playing position upon records of different diameters.

22. A graphophone including a cabinet, a motor driven turn-table including a record, a tone arm and reproducer mounted adjacent to the turn-table, a rock shaft operatively connected to the tone arm and reproducer, a pair of disks loosely mounted upon said shaft, driving means for rotating the disks upon the shaft, a clutch between the driving means and the disks, means for normally urging the clutch into operative position, a lever pivoted within the cabinet and operatively connected to the clutch, means upon one of the disks for normally engaging the lever to hold the clutch in the inoperative position and an arm upon the rock shaft for releasing the lever from said engaging means upon the disk when the tone arm and reproducer are moved to the end of the playing position of each record.

23. A graphophone including a cabinet, a motor driven turn-table including a record, a tone arm and reproducer mounted adjacent to the turn-table, a rock shaft operatively connected to the tone arm and reproducer, a pair of disks loosely mounted upon said shaft, driving means for rotating the disks upon the shaft, a clutch between the driving means and the disks, means for normally urging the clutch into operative position, a lever pivoted within the cabinet and operatively connected to the clutch, a pivoted arm upon said lever, a catch upon the lever normally engaging the arm, a pin upon one of the disks normally engaging the arm to hold the clutch in the inoperative position, and an arm upon the rock shaft arranged to engage the catch and release the pivoted arm from engagement with the pin when the tone arm and reproducer are moved to the end of the playing position of each record.

24. A graphophone including a cabinet, a motor driven turn table including a record, a tone arm and reproducer mounted adjacent to the turn table, a rock shaft operatively connected to the tone arm and reproducer, a pair of disks loosely mounted upon said shaft, driving means for rotating the disks upon the shaft, a clutch between the driving means and the disks, means for normally urging the clutch into operative position, a lever pivoted within the cabinet and operatively connected to the clutch, a pivoted arm upon said lever, a catch upon the lever normally engaging the arm, a pin upon one of the disks normally engaging the arm to hold the clutch in the inoperative position, an arm upon the rock shaft, and a set screw in said arm arranged to engage the catch and release the pivoted arm from engagement with the pin when the tone arm and reproducer are moved to the end of the playing position of each record.

25. A graphophone including a cabinet, a motor driven turn table including a record, a tone arm and reproducer mounted adjacent to the turn table, means for automatically moving the tone arm and reproducer out of engagement with the record and beyond the periphery of the turn table after each record has been played, means for automatically moving the tone arm and reproducer to the starting position after each new record has been placed upon the turn table, a bar pivotally mounted at one end within the cabinet, a rod slidably mounted upon the bar and arranged to operatively engage the starting lever of the motor, means for sliding said rod into position to start the motor, a trigger upon the bar arranged to hold the rod in the operative position, a rotatable disk adjacent to the rod provided with a plurality of pins of different lengths arranged to trip said trigger and means for swinging the bar upon its pivot to allow any desired pin to trip the trigger.

26. In a device of the character described in claim 25, a manually operated rock shaft extending through the cabinet, and an arm upon said rock shaft arranged to be moved into engagement with the trigger to trip the same.

In testimony that I claim the above, I have hereunto subscribed my name.

HENRY A. KOESTER.
